CARD OR PRICE TICKET HOLDER

Edmund J. Baas, Rochester, N. Y.

Application June 12, 1935, Serial No. 26,300

3 Claims. (Cl. 248—33)

The present invention relates to card holders and is especially useful as a price tag holder in connection with articles on window display. It has to do moreover particularly with holders for price tags as employed in connection with shoes and like articles which are commonly turned and tilted at various angles in a display case or window, not only for the purpose of creating an attractive display, but in many instances for the purpose of emphasizing some particular portion of the displayed article.

In the window display of shoes it is most common to exhibit the same upon forms within the shoes, and these forms constitute, in this instance, convenient supports for price tag holders although the variety of tilted or angled positions of the displayed shoes makes it a primary consideration that the tag holder be not only of a simple, inexpensive nature, but readily adjustable both horizontally and vertically to present a full face view of the tag from the front, irrespective of the particular position of the shoe.

It is for the above reasons that my invention proposes a universally adjustable tag holder capable of supporting a tag in a perpendicular position to full front view irrespective of the tilt or angle of its support, as well as one which will be durable, cheap and will permit of ready interchange of tags.

These objects are realized and the resulting advantages obtained by the device which will now be described in detail with reference to the accompanying drawing, which latter forms a part of this specification and in which

Figure 1 is a perspective view illustrating the practical application of my invention in connection with a shoe on display.

Figure 2 is a vertical sectional view longitudinally through a portion of the support, showing my improvement in side view and partly broken away and in section.

Figure 3 is a similar view transversely of the support.

Figure 4 is a top plan view of the parts shown in Figures 2 and 3, and

Figure 5 is a view similar to Figures 2 and 3 showing a slight modification.

Referring now to these figures, my invention proposes a tag holder which preferably, although not necessarily, consists of a spherical or ball-like member 10 having a card receiving slot 11. The slot 11 is of a width to receive and frictionally hold a price ticket or card and is preferably of a depth just sufficient for this purpose, and less than half the diameter of the member 10.

As above stated the member is preferably spherical although for the purposes of the present invention it would suffice that that portion of its surface lying opposite to and beyond the slot 11 be spherical or in other words that the member 10 present a spherical surface of somewhat more than half the diameter of the member. The member 10 is seated, in use, in a shallow socket, the socket also being of a depth less than half the diameter of the member, and in this socket, the member 10 of its own weight creates sufficient friction between its spherical surface and the wall of the socket to hold the member in various positions to which its obvious universal adjustability adapts it to be moved.

The socket receiving the member 10, as above described, may be formed in any suitable support which, as shown in Figure 1, for instance, may be a pedestal 14, the concave socket 13 being formed in the top of the pedestal. At its lower end the pedestal 14 is formed with a stem 15 for disposition in a conformable bore 16 of a shoe form 17 or other similar display holder.

On the other hand, the member 10 may be disposed with its spherical surface in a similar socket 18 in the top surface of the shoe form 17 and the latter may have in fact both a socket 18 and a bore 19 depending centrally of the socket so that it is permitted to either place the member 10 directly in the bore 18 or if so desired utilize the member 10 in the bore 13 of the pedestal 14 and seat the latter by means of its stem 15 in the bore 19, as shown in Figure 5.

It is obvious from the foregoing that since the socket in either of the above instances is of a depth less than half the diameter of the member 10, the latter has a very substantial range of universal adjustment so that the card 20 disposed in the slot 11 of this member may be tilted to various positions vertically and horizontally and in this way compensate for the horizontal angling or vertical tilting of a shoe in connection with which the improved tag holder is employed. Thus while the invention may be applied to various articles it is especially desirable in connection with the window display of shoes, the forms or holders of which constitute effective supports for the tag holding member, and the various positions of which on display utilize to the fullest extent the universal adaptability of the member 10 so that the price tag supported thereby may be maintained in an upright position with its full face to the front of the display window irrespective of the tilted position of the shoe.

The tag holding device of my invention may be economically formed of various materials insur-

ing almost unlimited life, may be easily stored in disuse without danger of deterioration, may be quickly applied and adjusted in use, and will add to, rather than detract from, the appearance 5 of a window display of shoes as a whole.

What is claimed is:

1. A card holder consisting of a support having a socket presenting a concave seat, and a ball having a card holding means, said ball being retained solely by its own weight in said socket and universally movably adjustable for presenting a card, held thereby, at various angles relative to the vertical axis of the support.
- 10 2. A card holder consisting of a support having

a socket, and a member having card supporting means and having a socket engaging surface seated in said socket and universally movably adjustable with respect thereto, the weight of the member constituting the sole means for maintaining the same with its card in various adjusted positions.

3. A card holder consisting of a support having a bore, a pedestal having an upper concave socket, and a lower stem seated in the bore of the support, and a member having card holding means and a spherical surface universally movably seated in the socket of the pedestal.
